CHORD PLAYING UNIT FOR AN ELECTRONIC ORGAN

James E. Rolfing, De Kalb, Ill.

Application June 25, 1958, Serial No. 51,533

Term of patent 14 years

(Cl. D56—2)

Fig. 1 is a right front perspective view of a chord playing unit for an electronic organ showing my new design; and

Fig. 2 is an end elevational view thereof.

The dominant features of the design reside in the portions shown in full lines.

I claim:

The ornamental design for a chord playing unit for an electronic organ, substantially as shown and described.
